UNITED STATES PATENT OFFICE.

JOHN HARRIS, OF CLEVELAND, OHIO.

CARBURETER.

1,066,608.

Specification of Letters Patent.

Patented July 8, 1913.

Application filed November 30, 1910. Serial No. 594,826.

To all whom it may concern:

Be it known that I, JOHN HARRIS, a citizen of the United States, residing at Cleveland, in the county of Cuyahoga and State 5 of Ohio, have invented a certain new and useful Improvement in Carbureters, of which the following is a full, clear, and exact description, reference being had to the accompanying drawings.

- 10 This invention relates to carbureters for mixing air and volatile liquid fuel for use in explosive engines, and has for its objects the provision of a device in which the liquid fuel is introduced into the carbureting chamber in the exact proportion required by the speed of the engine; in which the velocity of the current of air past the liquid discharge nozzle is constant at all times irrespective of variations in the speed of 15 the engine; in which the air supply can be adjusted to enable the carbureter to be used with all varieties of engines; in which the minimum air supply can be definitely and adjustably set to cause the engine to run 20 smoothly at very low speeds; in which the amount of mixture supplied to the engine can be instantaneously varied without changing the proportions of air and fuel contained therein; in which the relative proportions of fuel and of air supplied can be 25 easily adjusted; and in which the adjusting parts can be actuated to produce a momentary over-supply of fuel to aid in starting the engine.
- 30 Further objects and advantages will appear from the following description and claims.

One embodiment of my invention is illustrated in the accompanying drawings, in 35 which—

Figure 1 is a side elevation of my complete carbureter; Fig. 2 is a top plan view thereof; Fig. 3 is a central vertical cross sectional view thereof; and Fig. 4 is a longitudinal cross sectional view of the carbureter taken on the line A—A of Fig. 3.

Describing the parts by reference characters, 1 denotes a liquid fuel chamber, and 40 2 a carbureting chamber having at its top a threaded projection 3 whereby it may be attached to the inlet pipe of an explosion engine, said inlet pipe being shown at 3^a in Figs. 1 and 3 in dotted lines. This carbureting chamber is shown as vertically positioned, which I consider the preferable, though not indispensable, arrangement, and

the fuel chamber is rigidly attached to the side thereof by brackets 1^a and 2^a carried by the chambers 1 and 2 respectively and held together by screws 4. A fluid discharge nozzle 5 extends into the carbureting chamber 2 and is connected with the liquid fuel chamber by means of a pipe 6, preferably provided with a clean out opening closed by a plug 7. This pipe can be attached to the fuel chamber in any convenient manner, the present mode including the lock nut 8 being illustrated merely, and inside this chamber said pipe is connected with an upwardly extending tube or cylinder 9 having therein a closely fitting plunger 10, and having in one side and near the bottom thereof, an elongated slit 11. This slit is preferably about .008 inch wide, being made with a 32 Brown and Sharpe gage saw and has a length greatly in excess of its width, as shown. The tube 9 need not necessarily be located inside the fuel chamber but may be carried at any convenient point, provided only that slit 11 be in free communication 50 with the liquid fuel and entirely submerged therein.

Suitable means is provided for maintaining the level of the liquid fuel in chamber 1 at a constant height, such height being 55 preferably in the same horizontal plane as the discharge orifice of the nozzle 5 and in any case not higher than said orifice. In the embodiment shown herein, this means comprises a float 12 connected to a valve 13 by means of an arm 14 pivoted at 15 and having a forked end 16 adapted to engage a projecting shoulder 17 carried by the valve stem 18. This valve is disposed in a lateral projection 19 carried by chamber 1 60 and the fuel pipe from the storage tank (not shown) is connected to the threaded nipple 20 so as to discharge into the space 21 above the valve. The upper part of this projection is closed by a screw plug 22 65 which may be removed to allow disassembling or regrinding of the valve. The lower portion of the valve stem is guided by a sleeve 23 extending downwardly from the projection 19.

The chamber 1 is closed at the top by a plate 24 having a suitable aperture 25 for the tube 9 and is held in place by a spring arm 26 pivotally secured to a lug carried by the side of the chamber 1, as indicated at 26^a, and ending in a knob 27 adapted to engage a recess 28 in the cover.

29 is a handle by which the arm may be raised and swung to one side to release the cover.

5 Mounted upon shafts 30 journaled in opposed walls of the carbureting casing are two leaves or doors 31, adapted to swing together into the inverted V position shown in Figs. 3 and 4 to substantially close the air inlet passage, or to swing apart against the tension of a coiled spring 32 connected at each end to an arm 33 carried by each of the shafts 30, outside the casing 2. Each of these arms is shown as provided with notches 33^a to permit adjustment of the spring. The free edges of the doors or leaves 31 lie substantially in the plane of the discharge orifice of the nozzle 5 and are cut away at 34 to prevent complete obstruction of the air passage and to accommodate 10 the nozzle. The inward or closing movement of the leaves or doors 31 may be limited in any convenient manner, as by triangular plates 35 carried by the opposed walls of the carbureting casing, which is shown as of rectangular cross section at 15 this point. Provision is also made for adjusting the limit of this closing movement, such provision, in the embodiment illustrated, comprising an arm 36 carried by one of the leaves and a set screw 37 threaded into a projection 38 formed on the carbureting casing and coöperating with said arm. A spring wire 39 or the like engages the milled head of the screw and impositively 20 and frictionally holds the screw in adjusted 25 position.

For the purpose of controlling the air flow and the fluid fuel flow, I have shown a butterfly valve 40 carried on a shaft 41, journaled in the casing above the nozzle 5 and the leaves or doors 31. This valve is of rectangular shape and coöperates with a web or ledge 42 having a similar shaped opening, as shown in Figs. 2 and 3. This valve is 40 operated by means of a lever 43 having a suitable eye 44 at one end for connection to the usual throttle valve rod (not shown) and also having a finger 45 adapted to contact with a set screw 46 adjustably threaded 45 into a boss 47 carried by the casing 2, whereby the closing movement of the lever is limited. The valve 40 is adjustably attached to the shaft 41 by the set screw 48. A bracket 49 is also carried by the carbureting casing 2 and projects outwardly adjacent to the plunger 10. Journaled in this bracket is a shaft 50, which carries an arm 51 contacting with the top of a plunger 10, and which also carries a lever 52 connected 50 to the lever 43 by a link 53. In the embodiment illustrated, this link is shown as made in two parts having right and left hand threaded portions 53^a and 53^b respectively connected by a turnbuckle screw 54 to permit their relative adjustment. A spring 55

surrounds the plunger 10 between the end of the tube 9 and a head 56, and tends to hold the plunger in raised position and, by its action on the arm 51, to hold the valve 40 also in open position.

It will be noted, also, that the discharge orifice 57 of the nozzle 5 is rectangular in shape to correspond with the openings between the leaves or doors 31 and through the ledge 42. I find that this design gives extremely 70 satisfactory results, though I do not consider it indispensable.

A plate 58 is carried beneath the air inlet end of the carbureting chamber and spaced therefrom a sufficient distance to 80 permit free access of air thereto. This plate may be carried directly by the nozzle, as shown, or it may be supported in any other convenient manner.

The operation of the device is as follows: 85 The discharge orifice of the nozzle 5 being not lower than the level of the fuel liquid in the chamber 1, no discharge ensues when the engine is still. If the engine be started its suction will draw fuel through this nozzle in proportion to the needs of the engine, and, at the same time, the air entering the bottom of the casing is directed by the inclined doors against the end of the nozzle, thus insuring the complete and uniform 90 carbureting of the air. Furthermore, the velocity of the air past the nozzle is always uniform irrespective of the engine speed, since, if more air is demanded, the leaves or doors automatically open against the tension 95 of the spring 32, thus increasing the area of the air inlet orifice. As a consequence of this action the carbureting of the air is the same at high speeds as at low speeds, since at high speeds the air is not 105 sucked past the nozzle at an increased velocity with consequent decrease in the thoroughness of mixing. The minimum air inlet orifice between the leaves 31 is adjusted by means of the screw 37 to the point which 110 causes the engine to run smoothly at the very lowest speed. As a consequence of this construction my carbureter can be applied to any engine and will operate the 115 engine smoothly.

It will be noted that the butterfly valve 40 and the fuel slot 11 are both of rectangular cross section, and are operated simultaneously by means of the link 53. As a consequence of this construction the rate of 120 closing the two can be made rigidly proportional to each other, so that the rate of air and fuel supply can be varied simultaneously without affecting their relative proportions. This relation can, however, be 125 varied by means of the turn-buckle 54 and by setting the butterfly valve 40 on its shaft.

It is also a well known fact that the starting of an explosion engine, particularly in cold weather, requires an initial small over- 130

supply of fuel or "priming charge." This can be obtained in my carbureter by actuating the throttle lever to produce (through the lever 43, link 53, lever 52, shaft 50 and arm 51) a single quick depression of the plunger 10, which then acts as a pump piston and ejects a sudden spurt of fuel through the nozzle, moistening the interior surface of the carbureter and the top of the plate 58, and encircling the mixture inspirated during the first few strokes.

Of course, during the operation of the engine the jarring given the fuel chamber produces oscillation of the surface of the fuel, particularly in case the carbureter be used on an automobile, for which it is particularly designed. This, however, is immaterial since the suction of the engine produces a sufficiently uniform fuel feed notwithstanding the fluctuations of the head of fuel in the supply chamber. It will also be noted that the automatic constriction of the air inlet passage by the leaves or doors 20 tends to produce a more uniform aspirating action on the fuel nozzle than in other carbureters with which I am familiar, since at low speeds the velocity of the air does not fall so markedly as to interfere with this action. Inasmuch as this constriction occurs almost exactly at the discharge outlet of the nozzle the velocity of the air current at this point is constant, and the aspirating action is constant; consequently the amount of fuel supplied will depend 35 solely upon what proportion of the slit 11 is uncovered. In other carbureters with which I am familiar this aspirating action falls off with the speed, thus giving a variable fluid feed incapable of exact control.

40 I prefer to form the whole carbureter, and particularly the tube 9 and plunger 10, of gun metal, since the peculiar lubricating qualities of gasoline upon this alloy causes the plunger to work with great smoothness.

45 While I have necessarily described my invention in detail, I do not propose to be limited to such details except as the same may be positively included in the claims hereto annexed, or may be rendered necessary by the prior state of the art.

Having thus described my invention, what I claim is:

50 1. In a carbureter, a liquid fuel chamber, a carbureting chamber associated therewith and having air inlet and mixture outlet ports, a fuel discharge nozzle in said carbureting chamber, a cylinder having a narrow slit in its wall, said nozzle being in communication with the interior of said cylinder and said slit being in communication with the fuel in said fuel chamber, a plunger in said cylinder, and means for actuating said plunger to cover a greater or smaller proportion of said slit.

55 2. In a carbureter, a liquid fuel chamber,

a carbureting chamber associated therewith and having air inlet and mixture outlet ports, a fuel discharge nozzle in said carbureting chamber, a cylinder having a narrow slit in its wall, said nozzle being in communication with the interior of said cylinder and said slit being in communication with the fuel in said fuel chamber, a plunger in said cylinder, a throttle valve in said carbureting chamber, means for actuating said throttle valve, and means for simultaneously actuating said plunger to cover a greater or smaller proportion of said slit.

3. In a carbureter, the combination of a carbureting chamber having an outlet, a valve controlling said outlet, a conduit for supplying liquid fuel to said carbureting chamber, means for maintaining a level of liquid fuel below the jet orifice of said conduit, means for operating said valve, and connections whereby the movement of said valve will automatically eject a priming charge of liquid fuel through the jet orifice.

4. In a carbureter, the combination of a carbureting chamber having an outlet, a valve controlling said outlet, a liquid fuel supply conduit projecting into the lower end of said chamber, means for operating said valve, connections whereby the operation of the valve operating means may eject a priming charge of liquid fluid through the jet orifice, and means for maintaining a level of liquid fuel normally below said jet orifice.

5. In a carbureter, the combination of a carbureting chamber having an outlet, a valve controlling said outlet, a liquid fuel supply conduit extending into said chamber, said conduit being provided with an elongated slit located below the jet orifice of said conduit, means for supplying liquid fuel through said slit and into said conduit, a slideable member associated with said conduit and adapted to control the flow of liquid through the slit, a spring tending to hold said slideable member away from the slit, means for operating said valve, and connections whereby the operation of the valve will produce a corresponding movement of said slideable member.

6. In a carbureter, the combination of a float feed chamber, a carbureting chamber, a conduit for supplying liquid fuel from the float feed chamber to the carbureting chamber, said conduit having a branch extending into the carbureting chamber and a vertical branch, the latter branch being provided with an elongated slit adapted to communicate with the liquid in the float-feed chamber, a slideable member associated with the last mentioned branch, a spring tending to elevate said member, a valve controlling the outlet from the carbureting chamber, means for operating the last mentioned valve, and connections whereby the closing movement of said valve will move the slideable member.

proportionately to cut down the effective length of said slit.

7. In a carbureter, the combination of a float feed chamber, a carbureting chamber, a cylinder having an elongated slit in its wall parallel to its axis and communicating with said float feed chamber, a conduit for supplying liquid fuel from said cylinder to said carbureting chamber, a slideable plunger in said cylinder, and adapted to coöperate with said slit in governing the flow of liquid to said carbureting chamber, a spring tending to hold said plunger away from said slit, a valve controlling the outlet from the carbureting chamber, means for operating the last mentioned valve, and connections whereby the closing movement of said valve will move said slideable member proportionately to cut down the effective length of said slit.
- 20 8. In a carbureter, the combination, with a carbureting chamber having a liquid discharge nozzle, a liquid fuel reservoir, and means for maintaining in said reservoir a level of liquid fuel below the discharge orifice of said nozzle, of a conduit connecting said reservoir and said nozzle, and a combined regulative valve and priming device in said conduit, said device being adjustable

to control the flow of liquid to said nozzle and also being operable to eject a priming charge of liquid therethrough.

- 30 9. In a carbureter, the combination, with a carbureting chamber having a liquid discharge nozzle therein, a liquid fuel reservoir, and means for maintaining in said reservoir a level of liquid fuel below the discharge orifice of said nozzle, of a cylinder having a narrow elongated slit in its wall substantially parallel with the axis thereof, said slit being in communication with the liquid in said reservoir and said cylinder being in communication with said nozzle, and a slideable plunger in said cylinder and coöperating with said slit to regulate the flow of liquid to said nozzle, said 35 plunger being operative when moved quickly forward, to eject a priming charge of liquid through said nozzle.

40 In testimony whereof, I hereunto affix my signature in the presence of two witnesses.

JOHN HARRIS.
